UNITED STATES PATENT OFFICE.

JAMES H. WELSH, OF MONMOUTH, ILLINOIS.

ROAD MAINTAINER AND GRADER.

Application filed May 8, 1926. Serial No. 107,663.

This invention relates to road maintaining machines and particularly to graders and scrapers, and the general object of the invention is to provide a road maintaining machine having a plurality of pairs of blades so arranged that dirt scraped from the road by the blades will first move to the center of the machine and will be next moved outward by a second pair of blades and that later the earth so scraped from the surface of the road will be smoothed and filled into any hollow spaces.

A further object is to provide means for raising or lowering the frame upon which the blades are mounted and means for reversing the blades.

My invention is illustrated in the accompanying drawings wherein:—

Figure 1 is a top plan view of a grader and maintainer constructed in accordance with my invention;

Fig. 2 is a section on the line 2—2 of Figure 1;

Fig. 3 is a section on the line 3—3 of Figure 1;

Fig. 4 is a plan view showing two graders joined together to form a duplicate drag.

Referring to these drawings it will be seen that the main frame of the scraper and grader is more or less rectangular in form and consists of angle irons 10, though of course, channel irons might be used. This main frame is braced by vertical and rearwardly extending intermediate irons 11. The main frame will have a width of approximately 8' more or less and attached to the forward corners of the main frame are hitch chains or rods 12, these chains or rods extending forward and convergently and being adapted to be connected to any suitable draft appliance. This main frame may be supported by means of wheels 14 mounted upon upwardly extending levers 15, all of the levers on each side of the main frame being connected by a common link 16 to an adjusting lever 17 operating over a sector rack 18. Thus, one side of the main frame may be raised and the other side depressed or the main frame raised bodily to any desired spaced relation to the road.

I have illustrated two sets of grader blades, the first set being approximately 3' 6" long and these blades being designated 19. These blades are operatively supported upon the longitudinal bars of the main frame and the cross bars 11 and ex-

tend outward beyond the main frame and inward of the braces 11. These grader blades are made of steel and pivoted on the main frame by suitable means and the blades are preferably concaved. Rearward of the blades 19 is a second set of blades 20 of the same character as the first set of blades but extending inward a greater distance so that the space between this second set of blades is less than the distance between the first set of blades. Preferably the two front blades are shorter than the rear blades. These rear blades 20 are preferably disposed to extend outward and rearward at a slight angle while the forward blades are disposed to extend outward and forward at a slight angle.

Disposed rearward of the blades 20 are the smoothing bars 21 of flat steel which have lugs pivoted to the main frame so that these smoothing bars are also tiltable as are the blades 19 and 20. These smoothing bars are preferably disposed approximately parallel to the blades 19 and preferably these bars abut against each other. Mounted upon the longitudinal braces 11 or in any other suitable position are the adjusting levers 22 operating over arcuate racks 23 and connected by links 24 to the upper ends of the legs supporting the front blades 19 and to the upper ends of the lugs which support the smoothing bars 21. Thus, by shifting the levers 22 the front blades 19 and the smoothing irons 21 may be shifted so as to change their inclination. The blades 20 are also mounted so that their inclination may be changed and to this end the blades 20 each having an upwardly projecting handle or lever 25 adapted to be held in any adjusted position by means of the usual latch engaging an arcuate rack 26. Thus by shifting the levers 22 and 25 the blades 19 and 20 and the smoothing bars 21 may be changed as to inclination. The operation of this grader or road maintainer is as follows:—The two front blades 19 move the dirt of the road towards the center of the machine and cut down all hummocks and ruts, the dirt of course, being removed into the low portions of the road. The two middle blades 20 move the dirt from the middle outward in opposite directions to the movement of the dirt by the two front blades. The two smoothing bars are disposed preferably on about a 20° angle and act to move the dirt from the second blades over the same ground as the blades, thus leaving a smooth

105
110

surface, filling up all depressions in the roadway and cutting down protuberances.

I claim:—

A road maintainer of the character described including an approximately rectangular frame, a pair of forwardly and downwardly curved grader blades pivotally mounted upon the frame and extending inward and rearward in angular relation to each other, a second pair of forwardly and downwardly curved grader blades disposed rearward of the first pair and extending inward and forward and pivotally connected to the frame, a pair of smoothing bars being flat and each being disposed at an angle to the line of draft and approximately parallel to the first named blades, the smoothing bars being pivotally mounted upon the sup-

porting frame, means for tilting the blades and said smoothing bars, including levers having linked connection with the first named blades and the smoothing bars, and separate, independently operable levers connected to the second named blades to tilt them, and means for holding the levers in adjusted positions, arms pivotally mounted upon the frame adjacent the corners thereof, supporting wheels mounted upon said arms, levers for each pair of supporting wheels and having linked connection to said arms whereby the wheels may be shifted nearer to or further from the frame.

In testimony whereof I hereunto affix my signature.

JAMES H. WELSH.
